ROTARY CLINKER COOLER

Alexander J. Roubal, Wauwatosa, Wis., assignor
to Allis-Chalmers Manufacturing Company,
Milwaukee, Wis., a corporation of Delaware

Application November 25, 1940, Serial No. 367,021

4 Claims. (Cl. 263—32)

This invention relates generally to cooling apparatus and more particularly to the type of apparatus adapted for use in cooling hot granular materials.

The cooling of lime is, by way of illustration, in many instances accomplished by passing a large quantity of cooling air through a rotary conveying drum in counterflow relation with respect to the movement of the lime therethrough. In most arrangements of this type, the cooling air passes through the drum in direct contact with the heated lime therein but it is also common practice to indirectly effect the desired degree of cooling by passing the lime through muffle tubes which extend longitudinally throughout the interior of the drum. This latter arrangement avoids fogging the cooling air with dust which in turn results in other advantages as stated in the patent to R. D. Cheesman et al. No. 2,218,873, Tube cooler, dated October 22, 1940. Consequently, indirect cooling is in some instances preferred with respect to kiln and cooler arrangements in which the cooling air which is heated in passing through the drum is introduced into the associated kiln to support combustion therein.

The quantity of air which is necessary in order to cool lime or other granular material to the required degree is, as particularly pointed out in the patent to R. C. Newhouse, No. 2,218,476, dated October 15, 1940, Rotary cooler, greatly in excess of that required for combustion purposes and its introduction into the kiln materially reduces the overall efficiency of the combination comprising the kiln and cooler.

It is therefore an object of this invention to provide an improved indirect cooler and furnace arrangement which adequately cools the hot material discharged from the furnace without introducing excess air into the furnace.

Another object of this invention is to provide an improved indirect cooler in which precooling of hot material is effected entirely by combustion air and in which the final cooling is effected entirely by air in excess of that required for combustion within the associated furnace.

Still another object of this invention is to provide an improved indirect cooler structure which provides separate noncommunicating precooling and final cooling chambers through which the clinker passes.

The invention accordingly consists of the various features of construction, combinations of elements and arrangements of parts as more par-

ticularly pointed out in the appended claims and in the detailed description in which:

Fig. 1 is a longitudinal vertical section of a kiln and cooler arrangement embodying the invention;

Fig. 2 is a transverse vertical section of the cooler taken on line II—II of Fig. 1;

Fig. 3 is another transverse vertical section of the cooler taken on line III—III of Fig. 1; and

Fig. 4 is still another transverse vertical section of the cooler and the stack connected housing taken on line IV—IV of Fig. 1.

Referring to the drawing and particularly Fig. 1, it is seen that the invention is illustrated in connection with the cooling of lime or other granular materials discharged from a kiln or furnace 1 having a burner 2 of conventional construction. The hot lime upon leaving the kiln enters a combined hood and spout structure 3 which conducts lime into the front or receiving end of a cooler 4 which is mounted for rotation on axially spaced, conventional roller supporting structures 5. Rotation of the cooler may be affected by the usual ring gear and motor driven pinion arrangement designated generally by numeral 10.

The rotary cooler comprises, particular reference being also had to Figs. 2, 3 and 4, an elongated cylindrical drum 6 having disposed thereon in a central air tube 7 which coats with the interior surface of the drum 6 and forms therewith an annular cooling medium conducting space 8 and an annular series of spaced muffle tubes 9 which surround the central air tube 7 and which are spaced from the interior surface of the drum 6 and from the exterior surface of the air tube 7. In other words, the muffle tubes 9 are disposed within and extend through the annular cooling medium conducting space 8. The muffle tubes 9 are supported by and extend through a front header plate 11, a rear header plate 12, and an intermediate partition plate 13. The central air tube 7 which also extends through and is supported in part by the partition plate 13, has its forward end disposed in abutting relation with the inner surface of the front header plate 11 and has its rear end disposed in abutting relation with a baffle plate 14 which is spaced from the rear header plate 12 and which has a central opening 16 therein placing the interior of the air tube 7 in communication with the space 15 provided between the rear header plate 12 and the baffle plate 14.

The front and rear header plates 11 and 12 are disposed adjacent to and close the respective

ends of the drum 6 and the partition plate 13 coacts with said header plates and divides the interior of the drum, i. e., the annular cooling medium conducting space 8, into a precooling chamber 17 and a final cooling chamber 18. The air tube 7 is provided with an annular series of openings 19 disposed immediately in front of the partition plate 13 whereby a cooling medium entering the rear end of the tube 7 may flow forward therein and out through the openings 19 and into the rear end of the precooling chamber 17. If desired, a combined baffle and partition plate 20 may be disposed partially within the air tube 7 and immediately in front of the cooling medium discharge openings 19 so as to prevent the cooling medium from entering the front portion of the tube which is surrounded by the precooling chamber 17. The drum 6 is provided with an annular series of openings 21 disposed immediately rearward of the front header plate 11 so that the cooling medium entering the rear end of the precooling chamber 17 through the openings 19 will flow forward therethrough and out the openings 21. A cooling medium collecting housing 22 encloses that portion of the drum 6 which contains the cooling medium discharge openings 21 and the combined hood and spout structure 3 is provided with a fluid conduit portion 23 which communicates with the interior of the kiln and which is connected to the cooling medium collecting housing 22 so that when a combustible supporting cooling medium such as air is employed, the cooling air which passes out of the precooling space 17 through the openings 21 is conducted into the kiln to support combustion therein.

The front end of the drum 6 is provided with a refractory lining 24 which is in part spaced from the front header plate 11 so as to form therebetween a material receiving chamber 26 and which is arranged to provide a central opening 27 through which extends the material conducting spout portion of the combined hood and spout structure 3. The rear end of the drum 6 is provided with a hood structure 28 adapted to receive the cooled material leaving the muffle tubes 9 and this hood structure is provided with a central opening 29 through which extends an air admission conduit 31. A blower 32 has its discharge 33 connected with the conduit 31 to deliver cooling air into the space 15 between the baffle plate 14 and the rear header plate 12. A relatively short conduit 34 of less diameter than the conduit 31 extends in sealed relation through the central opening 16 in the baffle plate 14 and coaxially into the discharge end of the conduit 31. Consequently, a portion of the air passing through the conduit 31 enters the conduit 34 and passes therethrough and into the central air tube 7. A damper 36 disposed within the conduit 34 controls the quantity of cooling air entering the central air tube 7. As previously indicated, the air which enters the rear end of the central air tube 7 flows forward therein, out through the openings 19, forward through the precooling zone 17, then out through the openings 21 into the housing 22 and then through the conduit 23 into the kiln 1.

The drum 6 is also provided with another annular series of cooling medium discharge openings 37 disposed immediately rearward of the partition plate 13 and with a second cooling medium collecting housing 38, which may be connected with a stack structure 39 (see Fig. 3) and which is disposed in sealed relation about that

portion of the drum which contains the openings 37. The air which enters the space 15 from the conduit 31 then flows forward through the final cooling space 18, out through the openings 37 and into the housing 38 and then into the stack 39.

The interior of the precooling and final cooling spaces are preferably provided with a series of axially spaced and staggered annular baffle plates 41 and 42 which are secured to the outer surface of the central air tube and to the inner surface of drum 6, respectively, as best shown in Figs. 2 and 3. The baffle plates 14, 41 and 42, and the combined partition and baffle plate 20 coact with each other and with the muffle tubes 9 to direct the cooling medium flowing through the precooling and final cooling spaces transversely with respect to the longitudinal axis of the muffle tubes 9 to thereby increase the rate of heat exchange between the material confined within said muffle tubes and the cooling medium flowing through said spaces.

The capacity of the blower and the dimensions of the air tube 7 of the precooling and final cooling chambers 17 and 18, respectively, of the cooling medium discharge openings 19, 21 and 37, and of the conduits 31 and 34 are preferably so correlated that the quantity and the temperature of the combustion supporting cooling medium flowing out of the precooling chamber 17 and into the furnace through the openings 21, housing 22 and conduit 23, is commensurate with the combustion requirements of said furnace and that the quantity of cooling medium flowing through the final cooling space and to the stack 39 through the openings 37 and the housing 38 is sufficient to further cool the precooled material to the required predetermined degree. The proper dimensions for a particular application can be readily and accurately determined by any one skilled in the art and therefore sample calculations and a further description in this connection are not necessary for a complete understanding of this invention. However, a regulating damper such as the damper 36 should preferably be employed in order to compensate for variations in draft conditions and other variable factors which cannot be accurately predetermined for all conditions of operation.

The construction and the operation of the cooler 4 should be obvious in view of the foregoing detailed description. However, a feature of particular importance is the provision of separate non-communicating precooling and final cooling chambers, as this construction enables the use of a combustion supporting precooling medium in quantities commensurate with the combustion requirements of the kiln or furnace with which the precooling chamber communicates. In addition, the use of a precooling chamber which is entirely free from communication with the interior of the hot material conductor extending therethrough prevents any reaction taking place between the hot material which is to be cooled and the particular combustion supporting precooling medium employed and prevents the combustion supporting medium from becoming fogged with dust particles. Consequently, during normal operation the kiln or furnace is always supplied with the requisite quantity of a highly heated clean combustion supporting medium and as a result the combustion efficiency is materially improved, the operation of the furnace is inherently stable, and the reg-

ulation of the burner and/or furnace is greatly simplified.

The invention is of general application and although it has been disclosed in connection with a muffle tube cooler in which both the precooling and final cooling chambers are free from communication with the interior of the hot material conductor, it should be understood that the final cooling chamber may communicate with the interior of the hot material conductor, that different cooling mediums may be employed in the precooling and final cooling chambers and that it is not intended to limit the invention to the exact details of construction and mode of operation herein shown and described as various modifications within the scope of the appended claims may occur to persons skilled in the art.

It is claimed and desired to secure by Letters Patent:

1. In combination with a furnace, means for conveying and cooling the hot material discharged from said furnace comprising an elongated drum, means dividing the interior of said drum into separate, non-communicating precooling and final cooling chambers, a plurality of material conveying conduits extending through said dividing means and through said precooling and said final cooling chambers, an air tube extending through said final cooling chamber, through said dividing means, and into said precooling chamber, fluid conveying means operatively connecting said precooling chamber with the combustion space of said furnace, and means including said air tube operative to flow a quantity of combustion supporting cooling medium commensurate with the combustion requirements of said furnace through said precooling chamber and to flow a quantity of cooling air sufficient to further cool said material to a predetermined degree through said final cooling chamber.

2. In combination with a furnace, means for conveying and cooling the hot material discharged from said furnace comprising an elongated rotary drum, means dividing the interior of said drum into separate, non-communicating precooling and final cooling chambers, a central air tube extending through said final cooling chamber, through said dividing means, and into

said precooling chamber, a plurality of spaced muffle tubes arranged to surround said air tube and to extend through said dividing means and through said precooling and final cooling chamber, fluid conveying means operatively connecting said precooling chamber with the combustion space of said furnace, and means including said air tube operative to flow a quantity of combustion supporting cooling medium commensurate with the combustion requirements of said furnace through said precooling chamber and said fluid conveying means and to flow a quantity of cooling air sufficient to further cool said material to a required predetermined degree through said final cooling chamber.

3. A cooler for granular materials comprising an elongated drum, means dividing the interior of the drum into separate, non-communicating precooling and final cooling chambers, a central air tube extending through said final cooling chamber, through said dividing means, and into said precooling chamber, a plurality of spaced muffle tubes arranged to surround said air tube and to extend through said dividing means and through said precooling and final cooling chambers, and means including said air tube for effecting a flow of separate streams of cooling air through said precooling and said final cooling chambers.

4. In combination with a furnace, a hot material conveying conductor arranged to receive the hot material discharged from said furnace, a precooling conductor, a final cooling conductor, said precooling and final cooling conductors being arranged to flow separate streams of cooling medium in non-mixing relation with respect to each other and in heat exchanging relation with respect to different portions of said material conductor and out of contact with the hot material passing therethrough, and means for effecting the flow of said separate streams of cooling medium including connections operative to conduct the stream of cooling medium which flows through said precooling conductor and in heat exchanging relation with respect to a portion of said material conductor into the combustion space of said furnace.

ALEXANDER J. ROUBAL.
